UNITED STATES PATENT OFFICE

2,551,362

WINDING MACHINE

Ben Carter and Eric Carter, Bolton, England

Application July 24, 1945, Serial No. 606,846
In Great Britain December 11, 1943Section 1, Public Law 690, August 8, 1946
Patent expires December 11, 1963

10 Claims. (Cl. 242—43)

1

This invention relates to winding machines of the type having a bobbin holder for receiving and driving the bobbin to be wound, and having a guide movable alongside the bobbin for feeding the wire, thread or other elongated material to the bobbin and "laying" it as the bobbin rotates.

It is desirable in machines of this type to be able to vary the total traverse of the guide, for example to suit bobbins of different length, and also to be able to vary the pitch of traverse, that is to say the number of turns per inch in the length of the bobbin. It is also desirable to be able to make adjustments for these purposes without interfering with the continuous operation of the machine.

This invention has for its object, therefore, to provide a mechanism which gives an infinitely-variable adjustment both of the length of traverse and the pitch of traverse, and which also can give a variable period of dwell at each end of the traverse movement.

The invention comprises pivotal means for moving the guide, and means for varying the position of the pivot so as to shorten or lengthen the guide's total movement. The invention also comprises pivotal means for imparting a step-by-step motion to the guide-moving means, and means for varying the position of the pivot so as to shorten or lengthen the individual increments of the guide's movement.

Considered from another standpoint, the improved machine comprises a continuously-operable uni-directional driving member, means for converting the continuous uni-directional motion into a step-by-step uni-directional movement, and further means for converting the step-by-step uni-directional movement into a step-by-step to-and-fro movement; with means for varying the size of step in the step-by-step motion and means for varying the extent of the to-and-fro motion.

The invention is illustrated in the accompanying drawings, wherein—

Fig. 1 is a side view of the mechanism, the bobbin holder being viewed endwise;

Fig. 2 is a plan of the same;

Fig. 3 is a front view;

Fig. 4 is an enlarged sectional view of the means for holding and driving the bobbin;

Fig. 5 is a fragmentary view, partially in section, of an alternate cam arrangement for the main cam drive;

Fig. 6 is a view of the same mechanism taken at right angles to the view shown in Fig. 5;

Fig. 7 is a fragmentary top plan view of the same mechanism; and

Fig. 8 is a plan view of the lever bar, cam frame, and associated mechanism.

Referring to Figs. 1, 2 and 3, the machine comprises a frame indicated generally by 1, a driving

2

motor 2 mounted in the lower part thereof, a counter-shaft 3 for the motor (driven by variable speed pulleys 4 and 5 and belt 6), a bobbin holder above the frame (described in detail below), and means such as a belt 7 and pulleys 8 and 9 for driving the bobbin holder from the counter-shaft 3. The counter-shaft 3 also carries a worm 10, which drives a worm wheel 11 on a vertical shaft 12 whose upper end carries three identical heart-shaped cams 13 arranged at 120° pitch, and positioned just below the top plate 1a of the machine frame 1.

Slidable in guides 14 across the front end of the machine, such guides extending from the end 15 of the top plate 1a, is a traverse bar 15, to which is rigidly secured the guide 16, this guide embodying spaced plates 17 which slightly separate the multiple wires being wound, a steady roller 18, and a final guide roller 19. A clamp (not shown) may be incorporated between the rollers 18 and 19 for holding the ends of the severed wire when the bobbin is being changed. As the traverse bar 15 moves to-and-fro in its mountings, the guide 16 moves to-and-fro over the length of the bobbin in the bobbin holder.

The bobbin holder (see Fig. 4) comprises a headstock 20, with spindle 21 carrying the pulley 9, and a tailstock 22 with retractable spindle 23, the tailstock being of clamp form, with tightening lever 24 for gripping the spindle 23 in its advanced position. The forward end of headstock spindle 21 has a centre plug 21a to enter the bore of the bobbin shown in broken lines at 60, this being on an interchangeable plate 21b, held in position by the threaded inner terminal 20a of spindle 21 which passes through the headstock and has a knurled knob 61 at its outer end. A pin 21c carried by such plate enters a hole in the bobbin flange to form the driving connection. The tailstock spindle carries a rotatable centre 23a mounted on an anti-friction bearing 62, and has a rubber or like pad 23b to absorb the shock and reduce the noise of contact with the tailstock.

The traverse bar 15 is pivotally connected at 15a to one end of a lever or rocker arm 25 which is mounted on a pivot 26a extending downwardly from a nut 27 on a lead screw 28 mounted in the fixed bearings 29, and the other end of such arm 25 is connected to a cam frame 30 hereinafter referred to. Such lead screw 28 is manually rotatable by means of a hand-wheel 31 and bevel wheels 32, to vary the position of the nut 27 and thereby vary the pivotal relationship of the nut 27 and lever arm 25, the arm being slotted, as shown at 64 (see Figs. 2 and 8), to receive the pivot 26a, and the pivot having clamping means such as nut 26 to lock it in the adjusted position on the arm 25. Although the manual adjustment means is shown towards the

rear of lead screw 28, it could be at or near the forward end, and in such case the bevel wheels could be dispensed with, the hand-wheel 31 being mounted on the end of lead screw 28.

Below the said other end of such lever arm 25 is a vertical shaft 33 carrying the main cam 34 near its top end, the cam being keyed to the shaft as shown at 34a, which cam is heart-shaped and operates the said cam frame 30 to-and-fro to oscillate the lever arm 25 about its pivot 26a. The said shaft 33 is not power driven, but it carries three one-way roller and wedge clutches 35, each of which is operated by a rack 36 mounted to reciprocate in suitable guides 37. Each rack engages an exteriorly-toothed outer part 35a of the clutch so as to oscillate that part to-and-fro. These racks 36 are connected, respectively, to three pivotally-mounted rods 38, whose other ends are operated, respectively, by the said identical, oppositely-disposed cams 13 on shaft 12.

Actually, the cams 13 engage rollers 13a on lateral extensions 38a of rods 38, whilst compression springs 36a cooperate with the racks 36 to keep the rollers 13a in contact with the cams 13. The arrangement is such that as the cams 13 rotate, the said rods 38 are oscillated, and first one and then another gives an increment of movement (in the same direction) to the main cam shaft 33. Such rods 38 are each pivoted in a bar 39 which incorporates a pair of nuts 40 on two additional lead screws 41 so that, by rotation of these lead screws 41, the position of the pivots may be varied and the effective stroke of the cams thereby adjusted. The nuts 40 secured to the bar 39 are transversely movable by means of the lead screws 41, i. e.: rotation of the threaded lead screws 41 imparts lateral movement to the congruently threaded nuts 40 which are secured against rotation. Thus the bar 39 may be made to selectively traverse the lead screws 41. It is evident that with the changing of the fulcrum or pivot point, the stroke of the racks 36 are likewise effected. For example, if moved leftwardly, Figs. 1 and 8, the bar 39 alters the pivot point of the rods 38. With the stroke of the extensions 38a remaining constant, the stroke of racks 36 will therefore increase. Analogously, rightwardly positioning of bar 39 results in a reduction of the stroke of the racks 36.

The controlled variance in the racks 36 produces a similar variance in the increments of rotation of the main cam shaft 33. As shown, the rods 38 have a universal mounting in the said bar 39, being retained in position by the attached bosses 39a. Each lead screw 41 carries at its forward end a toothed wheel 42, both of which mesh with a wheel 43 operable by means of a hand-wheel or finger knob 44. Rotation of member 44 rotates lead screws 41 to traverse pivot bar 39.

The cam frame 30 has supporting guides 45 carried by brackets 46, and has upstanding rollers 47 to engage the cam at opposite sides. A slotted lug 48 at the rear end of the lever arm 25 receives a pin 48a carried by the cam frame 30.

In use, the motor 2 drives the bobbin holder, and also the three identical cams 13. These cams 13 impart step-by-step rotation to the main cam 34, the size of step depending on the position of the pivot bar 39 for the rack-operating rods 38, and the main cam 34 oscillates the slotted lever arm 25 to reciprocate the traverse bar 15 and guide 16. The total length of traverse depends upon the position of the pivot 26 for the slotted lever 25.

In order to obtain a dwell (if required) at the end of the traverse of bar 15, the pivot 15a, which depends from a block 15b carried on the upper surface of said bar 15, engages the bar 15 indirectly by means of the opposed screws 15c. The traverse bar is provided with an elongated slot 63 through which a pin 66 connecting block 15b and pivot 15a passes. In Fig. 2 screws 15c are shown in contact with block 15b so that no dwell would result. By retracting one or both screws a lost motion is introduced between lever 25 and bar 15 at each end of the traverse.

The spaced plates 17 on the guide 16 are secured by a wing nut 17a on its supporting stud, and such stud is movable in a slot 17b to vary the position of the plates 17 on the guide. The steady roller 18 and guide roller 19 may be similarly adjustable.

It is believed that the operation of the machine will be largely clear from the foregoing description. Motor 2 drives main drive shaft 3, which, in turn, drives the rotatable bobbin holder. Drive shaft 3 further imparts rotation to cam shaft 12 through the worm gear connection. Cams 13 are keyed to cam shaft 12, and accordingly rotate therewith. This rotation imparts a rocking movement to rods 38 which are fulcrumed at 39. This imparts a rocking movement to the opposite ends of rods 38, which opposite ends are connected with racks 36. These racks engage pinions 35a which operate one-way roller and wedge clutches 35. Thus, there is imparted to cam shaft 33 alternating rotary movement. Speed of rotation of this shaft is varied by varying the position of fulcrum 39 providing the intermediate supports for rods 38. There is thus provided a simple and inexpensive variable speed mechanism for driving cam shaft 33.

Cam 34 is, of course, keyed to shaft 33, and as cam 34 rotates it imparts reciprocating movement to cam frame 30. This, in turn, imparts rocking movement to main lever arm 25, the opposite end of which is operatively connected to the traverse bar 15 which supports the guide rollers for the wire being wound upon the bobbin. Variation in traverse of this bar is effected by adjusting the position of the pivot 26a intermediate the ends of lever arm 25. Such adjustment is effected by loosening nut 26, and then rotating hand-wheel 31 which rotates lead screw 28.

In the event that no dwell is desired at the end of each traverse of the traverse bar, screws 15c are tightened so that there is no relative movement between such screws and block 15b. In the event, however, that some dwell or lost motion is desired at the end of each traverse, screws 15c are appropriately moved outwardly from tight engagement with block 15b, and accordingly, at the end of each traverse, return movement of lever arm 25 imparts no movement to traverse bar 15 until the latter has moved far enough to contact the opposite screw 15c.

Referring now to Figs. 5, 6 and 7, an alternative cam arrangement is shown for the main cam drive. The upper end of shaft 33, carrying the one-way clutches 35, is fitted with a bevel wheel 49 meshing with a similar wheel 50 on a horizontal shaft 51. Such shaft also carries a barrel cam 52, in the groove 53 of which is a roller 53a carried from a sliding bar 54 which, in turn, is mounted in the brackets 55. Lever arm 25 connects to this sliding bar 54 with a pin and slot connection at 56. The roller

53a and cam groove 53 are tapered, and by means of a set screw 57 the roller may be advanced into the groove, when required, to take up wear.

Whilst, in the example shown, there are three rods 38 for imparting motion to the main cam, there may be two only, or there may be more than three.

What we claim is:

1. A winding machine comprising a frame, a bobbin holder mounted on the frame arranged to receive and drive the bobbin to be wound, a guide mounted for reciprocating movement parallel with the axis of the bobbin for feeding the material being wound, and means for imparting step-by-step motion to the guide, such means including a rocker arm which is connected at one end thereof to the guide, a pivot receiving such rocker arm between the ends thereof to permit rocking movement of the rocker arm about said pivot, means for varying the position of the pivot relative to the frame for varying the traverse of the guide, means comprising a cam for imparting reciprocating movement to the opposite end of the rocker arm, means for imparting intermittent movement to the cam, and means for varying the distance of such movement.

2. A winding machine comprising a frame, a bobbin holder mounted on the frame arranged to receive and drive the bobbin to be wound, a guide mounted for reciprocating movement parallel with the axis of the bobbin for feeding the material being wound, and means for imparting step-by-step motion to the guide, such means including a rocker arm which is connected at one end thereof to the guide, a pivot receiving such rocker arm between the ends thereof to permit rocking movement of the rocker arm about said pivot, means for varying the position of the pivot relative to the frame, a cam frame connected with the opposite end of the rocker arm, a cam for imparting reciprocating movement to the frame, a shaft carrying the cam, a plurality of clutches carried on the shaft, rods for imparting intermittent movement to the clutches, cams for driving such rods, and means for varying the stroke of such rods.

3. A winding machine comprising a frame, a bobbin holder mounted on the frame arranged to receive and drive the bobbin to be wound, a guide mounted for reciprocating movement parallel with the axis of the bobbin for feeding the material being wound, and means for imparting step-by-step motion to the guide, such means including a rocker arm which is connected at one end thereof to the guide, a pivot receiving such rocker arm between the ends thereof to permit rocking movement of the rocker arm about said pivot, means for varying the position of the pivot relative to the frame for varying the traverse of the guide comprising a rotatable lead screw which carries the pivot, a cam frame connected with the opposite end of the rocker arm, a cam for imparting reciprocating movement to the frame, a shaft carrying the cam, a plurality of one-way clutches carried on the shaft, racks for imparting intermittent movement to the clutches, means for driving such racks, and means for varying the stroke of such racks to vary the size of the step in the step-by-step motion.

4. A winding machine comprising a frame, a bobbin holder mounted on the frame arranged to receive and drive the bobbin to be wound, a guide mounted for reciprocating movement par-

allel with the axis of the bobbin for feeding the material being wound, and means for imparting step-by-step motion to the guide, such means including a rocker arm which is connected at one end thereof to the guide, a pivot receiving such rocker arm between the ends thereof to permit rocking movement of the rocker arm about said pivot, means for varying the position of the pivot relative to the frame, a drive shaft, means for revolving the drive shaft, a plurality of identical cams thereon set at equal angles around it, pivotally-mounted rods oscillated by such cams which impart step-by-step motion to the opposite end of the rocker arm, and means for varying the position of the latter pivot for varying the length of such steps.

5. In a machine for winding plural strands of wire and the like on a bobbin, the combination of a frame, a drive shaft journalled in the frame, a rotatable bobbin holder, and driving means connecting the drive shaft with the bobbin holder, a traverse bar mounted for sliding movement on the frame, wire guiding means carried by the traverse bar, means for moving the traverse bar to-and-fro comprising a lever arm connected at one end thereof to the traverse bar, a pivot supporting such arm intermediate its ends, the pivot being movable longitudinally of the lever arm to an adjusted, fixed position, means movable longitudinally of the frame for supporting such pivot, a cam frame mounted for sliding movement on the frame, means connecting the opposite end of the lever arm with the cam frame, a first cam shaft and a cam keyed thereto journalled in the frame, the cam engaging the frame and imparting reciprocating motion thereto upon rotation of such shaft, means for imparting rotation to such shaft comprising a second cam shaft operatively connected with the drive shaft, plural driving cams keyed thereto, a driving rod contacted by each of such driving cams, which cams impart rocking motion to such rods, pivots supporting the rods intermediate their ends, such pivots being movable longitudinally of the frame, and means connecting the opposite end of each rod with the cam frame to impart reciprocating movement thereto.

6. In a machine for winding plural strands of wire and the like on a bobbin, the combination of a frame, a drive shaft journalled in the frame and driving means for the shaft, a rotatable bobbin holder, and driving means connecting the drive shaft with the bobbin holder, a traverse bar mounted for sliding movement on the frame, wire guiding means comprising plural rollers carried by the traverse bar, means for moving the traverse bar to-and-fro comprising a longitudinally-slotted lever arm connected at one end thereof to the traverse bar, a pivot supporting such arm intermediate its ends, the pivot passing through such slot and being movable longitudinally thereof to an adjusted, fixed position whereby to adjust the distance of traverse of the bar, a lead screw supporting such pivot and means for rotating the lead screw, a cam frame mounted for sliding movement on the frame, pin-and-slot means connecting the opposite end of the lever arm with the cam frame, a first cam shaft and a cam keyed thereto journalled vertically in the frame, the cam engaging the frame and imparting reciprocating motion thereto upon rotation of such shaft, means for imparting step-by-step rotation to such shaft comprising a second cam shaft operatively connected with the drive shaft, plural driving cams keyed thereto, a driving rod contacted by each of such driving cams, which cams impart rocking

motion to such rods, pivots supporting the rods intermediate their ends, such pivots being movable longitudinally of the rods and longitudinally of the frame to an adjusted, fixed position to vary the traverse of opposite ends of the rods, a rack connected at the opposite end of each rod, a pinion engaged by each rack, and one-way clutch means connecting each pinion with the first cam shaft to impart such step-by-step rotation thereto.

7. In a machine for winding plural strands of wire and the like on a bobbin, the combination of a frame, a drive shaft journalled in the frame, a rotatable bobbin holder, and driving means connecting the drive shaft with the bobbin holder, a traverse bar mounted for sliding movement on the frame, wire guiding and tensioning means carried by the traverse bar, means for moving the traverse bar to-and-fro comprising a lever arm connected at one end thereof to the traverse bar, variable, lost-motion means in such connection to permit a dwell at the end of each stroke of the bar, a pivot supporting such arm intermediate its ends, means for varying the position of the pivot relative to the lever arm to vary the stroke of the traverse bar, a cam frame mounted for sliding movement on the frame, a pivot connecting the opposite end of the lever arm with the cam frame, a first cam shaft and a cam keyed thereto journalled in the frame, the cam engaging the frame and imparting reciprocating motion thereto upon rotation of such shaft, means for imparting variable speed rotation to such shaft comprising a second cam shaft operatively connected with the drive shaft, plural driving cams keyed thereto, a driving rod contacted by each of such driving cams, which cams impart rocking motion to such rods, pivots supporting the rods intermediate their ends, such pivots being movable longitudinally of the frame, and one-way clutch means connecting the opposite end of each rod with the first cam shaft.

8. In a machine for winding plural strands of wire and the like on a bobbin, the combination of a frame, a drive shaft journalled in the frame, a rotatable bobbin holder, and driving means connecting the drive shaft with the bobbin holder, a traverse bar mounted for sliding movement on the frame, wire guiding and tensioning means carried by the traverse bar, means for moving the traverse bar to-and-fro comprising a lever arm, a pair of spaced, adjustable stops carried by the traverse bar, one end of the lever arm being disposed between such stops to drive the traverse bar and to permit a dwell at the end of each stroke thereof, a pivot supporting such arm intermediate its ends, the pivot being movable longitudinally of the arm to an adjusted, fixed position, means for supporting such pivot in an adjusted, fixed position on the frame, a cam frame mounted for sliding movement on the frame, means connecting the opposite end of the lever arm with the cam frame, a first cam shaft and a cam keyed thereto journalled in the frame, the cam engaging the frame and

imparting reciprocating motion thereto upon rotation of such shaft, and means for imparting variable speed rotation to such shaft.

9. In a machine for winding plural strands of wire and the like on a bobbin, the combination of a frame, a drive shaft journalled in the frame, a rotatable bobbin holder, and driving means connecting the drive shaft with the bobbin holder, a traverse bar mounted for sliding movement on the frame, wire guiding means comprising plural rollers carried by the traverse bar, means for moving the traverse bar to-and-fro comprising a lever arm connected at one end thereof to the traverse bar, a pivot carried by the frame supporting such arm intermediate its ends, the pivot being movable longitudinally of the arm and of the frame to an adjusted, fixed position to vary the traverse of the bar, a first cam shaft and a cam keyed thereto journalled in the frame, driving means connecting the cam and the lever arm to impart reciprocating motion thereto upon rotation of such shaft, means for imparting rotation to such shaft comprising a second cam shaft operatively connected with the drive shaft, plural driving cams keyed thereto, a driving rod contacted by each of such driving cams, which cams impart rocking motion to such rods, pivots supporting the rods intermediate their ends, such pivots being movable longitudinally of the frame, and one-way clutch means connecting the opposite end of each rod with the first cam shaft to impart rotation thereto on movement of the rods.

10. A winding machine comprising a frame, a bobbin holder mounted on the frame arranged to receive and drive the bobbin to be wound, a guide mounted for reciprocating movement parallel with the axis of the bobbin for feeding the material being wound, and means for imparting step-by-step motion to the guide, such means including a rocker arm which is connected at one end thereof to the guide, a pivot receiving such rocker arm between the ends thereof to permit rocking movement of the rocker arm about said pivot, a cam for imparting variable, step-by-step reciprocating movement to the opposite end of the rocker arm, means for varying the position of the pivot relative to the frame for varying the traverse of the guide, and lost motion means for effecting a dwell adjacent the end of each traverse.
